SORTING APPARATUS

Charles M. Pierce, Detroit, Mich.; Luduska Pierce executrix of said Charles M. Pierce, deceased

Application July 27, 1934, Serial No. 737,266

7 Claims. (Cl. 194—103)

This invention relates to selecting and sorting devices for coin-controlled mechanisms and the like, and has for a particular object the provision of apparatus improved in sensitivity, efficiency, compactness and cost, for detecting and rejecting slugs or improper coins and for passing proper coins to a predetermined receptacle or mechanism.

Another important object of my invention lies in the provision of such sorting mechanism which is not only of extremely simple and sturdy construction but so compact, particularly in one dimension, that several complete sorting units may be installed in a relatively narrow and confined space.

A further object is the provision in such apparatus of a rotatable selecting element constituting an improvement upon that disclosed in my previously filed application Serial No. 688,596, filed September 8, 1933, particularly in that all possibility of clogging such element, either by the insertion in rapid succession of a number of slugs or improper coins, or by the insertion of an extremely light slug of insufficient weight to discharge itself from the wheel, is eliminated.

Still another object is the provision of means constituting an improvement upon the apparatus disclosed in said previous application adapted to prevent the lodging of a coin or slug upon the dividing partition which separates the receptacles for genuine and improper coins and slugs. Difficulty has heretofore been encountered with sorting devices, no matter how the actual selection is effected, whenever the elements to be sorted are dropped upon a partition representing a parting of the paths to the receptacles for accepted and rejected coins, inasmuch as occasionally a coin or slug is encountered which is of the precise weight represented by the positioning of the partition, as a result of which, particularly if the path down which such coin and slug elements pass is inclined sidewise, it is apt to fall directly and lodge upon the partition in such manner as to hang in such position and enter neither path.

Still further my present invention aims to provide improved means for adjusting and controlling the operation of the selecting element, and for rejecting undersized coins and slugs independently of the selecting element.

A still further object is the provision of improved means for assembling a plurality of such selecting devices in a unitary construction of compact nature adapted to afford means whereby coins of different denominations may be sorted

independently, but slugs and improper coins may be delivered to a common point of disposal.

Other objects and advantages will be apparent from the following description, wherein reference is made to the accompanying drawings illustrating preferred embodiments of my invention and wherein similar reference numerals designate similar parts throughout the several views.

In the drawings:

Figures 1 and 2 are front and side elevational views respectively of a pay station telephone instrument serving as an illustrative example of a coin-controlled device incorporating my improved slug-rejecting mechanism, and indicating the positioning of such mechanism therein;

Figure 3 is a rear elevational view of the upper portion of the instrument, showing one face of my improved slug-rejecting mechanism in elevation;

Figure 4 is an edge view of the slug-rejecting mechanism, removed from the casing;

Figures 5, 6 and 7 are elevational views of one face of such mechanism with the face plate removed, taken substantially on the line 5—5 of Figure 4 and looking in the direction of the arrows, progressively showing the travel therethrough of both a proper coin and an underweight slug, and illustrating the manner in which they are separated and the one delivered to the coin-receiving chute while the other is rejected;

Figure 8 is an elevation of the opposite face of the slug-rejecting mechanism removed from the casing, taken looking substantially as indicated by the arrow 8 of Figure 4;

Figure 9 is a view of the same face with the cover plate removed and corresponding to Figure 5 in its showing of the opposite face;

Figure 10 is a transverse section taken substantially on line 10—10 of Figure 8 and looking in the direction of the arrows;

Figures 11, 12 and 13 are elevational views of the interior, with the face plate removed, similar to Figures 5, 6 and 7 but showing the manner in which the apparatus is cleared and reset at the next actuation after an extremely light slug whose weight is insufficient to enable it to discharge itself has been fed into the machine and lodged in the wheel; and

Figure 14 is an enlarged detail of the partitioning and deflecting means.

Referring now to the drawings, reference character 20 designates the casing of a pay telephone instrument, with which my improved slug-rejecting means is for illustrative purposes shown asso-

ciated. It will be recognized, however, that my apparatus is equally utilizable in conjunction with other and indeed virtually any coin-controlled apparatus, and that if desired it may be used 5 purely for the purpose of sorting coins,—the telephone instrument having been selected by way of illustration because, since very little space is available in such instruments for installation of slug-rejecting mechanisms, it illustrates the compactness of construction into which my invention 10 may be embodied.

At the top of the telephone instrument is shown a coin gauge 21 having openings adapted to receive coins of the proper sizes, which openings 15 ordinarily form the tops of chutes for conducting the coins to the operating mechanism and thence to the cash box (22).

Within the casing and in the path of travel of such coins I provide a sorting assembly of 20 relatively flat construction. In the construction shown, two complete sorting devices are provided, one for sorting each of the most commonly imitated coins, although it will be readily perceived that if desired three such units might be similarly assembled, or one only provided. The assembly 25 is supported and the coin chutes and certain other parts are defined by the configuration of metal plates, which are assembled in stacked relation, as by means of screws 23. The assembly 30 incorporates a central plate, as 22, forming the main support, to and on opposite sides of which are arranged chute plates 26—28, which are cut out to form the coin chutes, presently to be described, while outside each of these is a face plate 35 as 25—27. All such plates are apertured as at 34 to receive and permit free rotation of the sorting discs 36—36a. Each of plates 26—28 is cut out to form a chute, as at 30—30a, the chutes being connected at their upper ends to the pockets in 40 the coin gauge and serving to conduct coins and slugs to the rotatable sorting elements 36—36a. Each of these chutes will also be seen to be so bent back upon itself as to eliminate any spin which may have been imparted to the coin upon 45 its insertion. The selector elements 36—36a are formed as discs shown as built of spaced circular plates, the central spacing element being cut out as at 50—50a to provide pockets adapted to receive coins and slugs fed thereinto, and are carried 50 by shafts 44—44a respectively, which are provided with needle point bearings rendering the discs rotatable with a minimum of friction, the outer bearings being carried by supporting brackets 48—48a mounted on face plates 27—25, 55 while the inner bearings may be carried by a single central bracket projecting between the selector discs and in substantially the same plane as central plate 22, or separate brackets may be used to assist assembly and enable separation of 60 the sections while preserving each intact. The central bearing bracket, designated 49, may also be supported from one face plate, as with bracket 48a, as shown in Figure 10.

Hair counterbalance springs 40—40a tend to 65 return each disc to a normal rest position which is determined by engagement of stop pins 41—41a with adjustable stops 42—42a. Rotative movement of the discs in the other direction is limited 70 by stop springs 63—63a, also engageable by said pins to limit the travel of the discs, while springs 63—63a also serve as return kickers, tending to throw the discs rapidly in the reverse direction when the latter are actuated with such severity 75 that the pins strike such springs hard enough to

flex them. The instrument is so adjusted that the impulse imparted to the disc by an overweight slug is sufficient to cause such reverse kicking of the disc. Springs 63—63a are adjustably carried by screws 64—64a, rotatably mounted in brackets 5 66—66a projecting from the face plates.

The stops 42—42a are so situated that when each disc is in the normal rest position, with its stop pin against abutment 41 or 41a, one of the coin-receiving slots or pockets, as 50—50a, is 10 aligned with the adjacent inlet chute 30 or 30a in such manner as to receive a coin therefrom. The hub portion 51—51a of each wheel is so positioned with respect to the outlet of the appurtenant chute that coins are forced to strike the 15 hub while traveling in a radial path with respect to the wheel before dropping into the pocket. The provision of the return bends in the delivery chutes in combination with the arrangement of the hubs in the aforementioned manner is such 20 that coins are introduced into the discs at a predetermined velocity with relation to their weight, and in effect dropped from a predetermined height into the pocket, and cannot by being thrown, pushed or snapped, be made to impact 25 the disc at greater than the fixed velocity. The adjustment of the parts, including the partitioning element presently to be described, is such that a proper coin sufficiently overcomes the resistance 30 of the spring to rotate the wheel far enough to carry the coin beyond the partition member, (52—52a) while if a lighter coin or slug be so inserted in one of the chutes and fall into the pocket of the selector wheel, its lesser mass and impact will be insufficient to rotate the wheel far 35 enough to carry the coin beyond the partition, and such spurious coin will fall from the disc upon the nearer side of the partition and be directed to receiving chute 60, whence it is guided into the coin return box 62 (first passing through 40 opening 54 in the case of disc 36).

A proper coin, introduced into chute 30 and falling from disc 36 to the left of partition 52, as viewed in Figures 5—7 and 11—13, is conducted 45 first to the bell 24, through chute 32, and thence to the coin release mechanism, generally designated 55 in Figure 2, through chute portion 33. It will be recognized that in Figures 5—7 and 9—13, the face plates 25—27 being removed, the chutes are shown as if open on one side, whereas they 50 would actually be closed by such plates, and that the pockets in the discs may also be closed on both sides. Similar action occurs when a proper coin is cleared by the disc 36a and drops to the right of partition 52a as viewed in Figure 9. The 55 coin then first strikes gong 54a and thereafter travels to the coin released mechanism through chute 33a.

The manner in which a proper coin, as 56 finds its way through the apparatus in the manner described is clearly illustrated in Figures 5 to 60 7, and it will be seen to be only necessary that the resistance of the hair spring 40 be so adjusted to the weight of a proper coin that such coins are but slightly heavier than the weight 65 required to make the disc stop directly over the partition, to render such coins just able to turn the selector wheel far enough beyond the partition so that such proper coins may fall upon the farther side of the dividing member 52, to insure 70 that all coins or slugs lighter than such proper coins will be cast to the right of the dividing member and so delivered to the rejector chute 60. As best shown in Figures 8 and 14, partition members 52—52a are adjustably carried by ad- 75

justing screws 65—65a, and the partition element proper is preferably formed of spring material, of such gauge as to be freely flexible under the impact of a coin or slug, as a result of which coins 5 striking such partition are bounced, and their delivery to one side or the other is thus insured even though they fall directly upon it. Since the entire selector mechanism may be inclined from the vertical, as best shown in Figure 2, so that 10 the coins tend to rest against one of the side plates defining the chutes, the bouncing action is particularly advantageous in preventing the resting of a coin against the partition in the lodged position in which it might be maintained with 15 greater ease by reason of such inclination.

The selector wheels are of course preferably of light construction and very freely rotatable, and the coin-receiving pockets as 50—50a therein are so contoured that centrifugal force generated by 20 a coin during its rotation with the disc assists in revolving it, and that after the wheel has turned through a sufficient angle, greater than 90°, a contained coin is free to roll out of the pocket upon whichever side of the partition it 25 may come substantially to rest with the stopping of the disc.

Each disc is shown provided with two oppositely disposed pockets, which may be identical, not only to preserve the balance of the disc but to 30 enable turning it a half revolution, and so bringing the other pocket into use, if wear from continued use affects the shape of the nose or toe of the pocket over which the coin rolls. Each pocket is preferably circular and of approximate 35 size to receive the intended coin desired to be accepted by the disc. The circular retaining portion of the pockets, further, extends sufficiently far around the coin when held therein to prevent the coin from rolling from the pocket until the 40 disc has turned through a relatively large angle exceeding ninety degrees, and to the point at which coins of a given weight are intended to be discharged. It will also be seen that by reason of the substantially diametrically opposed 45 position and relatively thin character of the arms forming the coin-pockets, approximately half the disc is open to receive coins or slugs introduced into the machine. By reason of this arrangement, the introduction of a very light slug which 50 is unable to turn the wheel far enough to discharge itself, does not clog the machine, as the next coin or slug element either falls upon the rim of the first and quickly discharges itself into the reject chute before the disc has turned 55 to the usual extent, or falls into the pocket beside the first, in which event the added impetus thus given the disc can virtually never, as a practical matter, be the exactly proper one required to turn the wheel to and discharge the load at the accept side of the partition element 60 52, so that both elements are either discharged by the underweight reject means above described or thrown out the reject slot by the overweight return mechanism presently to be described.

65 The resilient stop and kicker springs 63—63a with which each wheel is provided is so positioned, though adjustably held by screws 64—64a, that when the disc is rotated farther than the weight of an ordinary coin of the proper variety 70 is capable of rotating it, the stop pin strikes the spring, which returns the disc so rapidly as to push throw the coin in the reverse direction before it can clear the disc, thus forcing it to fall into the same reject chute 60 as underweight coins.

The assembly being intended for installation in inclined position, undersize release openings may be formed in the chutes 30—30a as at 70—70a respectively if desired, through which undersize coins may fall without passing through 5 the sorting means, although this is of course optional. Guiding means is provided such as the plate 11 for conducting such coins or slugs into the same coin return box 62.

While it will be apparent that the illustrated 10 embodiments of my invention herein disclosed are well calculated to adequately fulfill the objects and advantages primarily stated, it is to be understood that the invention is susceptible to variation, modification and change within 15 the spirit and scope of the subjoined claims.

What I claim is:

1. In a device of the character described, in combination with coin feeding means, selecting means comprising a rotatable coin receiving 20 element of low inertia and initial resistance to turning moment, rotatable through more than 90 degrees and having a pocket therein greater than 90 degrees but less than 180° in extent adapted to receive and hold coins delivered thereto, spring-counterbalancing means for said element, means for projecting coins into said pocket and against a portion of said element, and means for segregating coins in accordance with 25 the impetus imparted to the element, including 30 a partition against which coins may fall from said element yieldable in the direction in which the coins fall and adapted to give a reverse impetus thereto when fixed.

2. In a device of the character described, 35 selecting means including a counterbalanced rotatable selecting member from which coin elements and the like subjected to test, fall at different points along its path of movement in response to differences of mass of such elements 40 under test, inclined means for directing such falling elements in axially tilted position in a non-vertical path, separate receiving means for such elements of different masses, and partitioning and deflecting means appurtenant said inclined directing means and defining a line of 45 parting between the paths of coin travel to said receiving means, said partitioning and deflecting means being yieldable in the direction in which such coin elements travel. 50

3. In a device of the character described, selecting means including a counterbalanced rotatable selecting member from which coin elements and the like subjected to test fall at different points along its path of movement in response to differences of mass of such elements, 55 separate receiving means for such elements of different masses, inclined guide means for directing the fall of said elements while maintaining them axially tipped, and partitioning and deflecting means defining a line of parting between the paths of travel of coin elements of different masses passing along said guide means, to direct said elements to different ones of said receiving means, said partitioning and deflecting means being yieldable in the direction in which such coin elements fall, means for regulating the positioning of said partitioning and deflecting means, and means for varying the counterweight of said selecting member. 70

4. In a device of the character described, a selecting element of slight mass relatively to normal objects to be tested rotatable through a substantial fraction of a full revolution, spring counterbalancing means for said element, a sup- 75

- port for loads under test carried by said element and having a curved concaved supporting portion adapted to block movement of the load from said element during a portion of the revolution 5 thereof and to permit rolling of the load off said element in a relative position dependent upon the load, and means for segregating objects in accordance with the position in which they roll from said element.
- 10 5. In a device of the character described, a rotatable selecting element, supporting means carried by said element for sustaining thereon rollable articles to be tested, said supporting means including a curved concaved coin holding 15 portion outlying an article under test loaded upon said supporting means, said outlying portion blocking rolling movement of such loaded articles from said element during a portion of normal actuating rotative movement thereof and 20 projecting backward in a direction opposite to that of normal rotation of said element, means for delivering rollable articles to be tested to said element in such manner as to actuate the element with a severity dependent upon the mass 25 of the load, said element being of slight mass and mounted to offer slight resistance to turning moment, spring means yieldably resisting rotation of said element and so proportioned to the masses or normal loads to which the device is 30 desired to be subjected that said element is free to turn under actuation thereby sufficiently far to permit the load to roll over said projecting portion and from the element, and means for segregating objects in accordance with the position 35 at which they roll from said element, whereby the point in the path of movement of said element whereat a load is freed to roll therefrom is dependent upon the impulse imparted to the element thereby and so upon the mass of the 40 load, and whereby during rotation of said element the centrifugal force of a load is applied through said backwardly projecting portion to augment the turning moment applied to said element.
- 45 6. In a device of the character described, a rotatable selecting element of slight mass, spring counterbalancing means for said element, supporting means carried by said element for sustaining thereon rollable articles to be tested,
- said supporting means including a backwardly curved portion outlying an article under test loaded upon said supporting means, said outlying portion blocking rolling movement of such loaded articles from said element during a portion 5 of a normal actuating rotative movement thereof, means for delivering rollable articles to be tested to said element at an elevated position and in such manner as to actuate said element with a severity dependent upon the mass of the 10 load, said element being sufficiently rotatable and the spring means being proportioned to permit normal loads to travel through a position in which the load lies directly beneath the axis of the element, whereby said loads may roll from 15 the element at different positions in accordance with their mass, and means for segregating loads in accordance with the position at which they roll from said element.
7. In a device of the character described, a 20 rotatable selecting element of slight mass, spring counterbalancing means for said element, supporting means carried by said element for sustaining thereon rollable articles to be tested, said supporting means including a backwardly 25 curved portion outlying an article under test loaded upon said supporting means, the outlying portion being positioned to block rolling movement of such loaded articles from said element during a portion of a normal actuating rotative 30 movement thereof, means for delivering rollable articles to be tested to said element at an elevated position and in such manner as to actuate said element with a severity dependent upon the mass of the load, said element being sufficiently 35 rotatable and the spring means being proportioned to permit normal loads to travel through a position in which the load lies directly beneath the axis of rotation of the element, the outlying blocking portion being movable to a position of non-interference with rolling of a loaded article from said element when the load reaches such position beneath the axis, and means for 40 segregating loaded articles in accordance with the position at which they roll from the selecting element.
- 45

CHARLES M. PIERCE.
